UNITED STATES PATENT OFFICE.

WINFIELD S. LIVENGOOD, OF KANSAS CITY, MISSOURI, ASSIGNOR TO SMITH & SONS MFG. CO.,
OF KANSAS CITY, MISSOURI.

BALING-PRESS.

No. 927,807.

Specification of Letters Patent.

Patented July 13, 1909.

Application filed July 17, 1906. Serial No. 326,566.

To all whom it may concern:

Be it known that I, WINFIELD S. LIVENGOOD, a citizen of the United States, residing at Kansas City, in the county of Jackson and 5 State of Missouri, have invented certain new and useful Improvements in Baling-Presses, of which the following is a specification.

My invention relates to improvements in baling-presses, and relates more particularly 10 to double-acting or that type of press wherein two bales are delivered, substantially, at the same time.

My object is to produce a press of large baling capacity which may be operated at 15 minimum expense, and with these ends in view I make it as nearly automatic throughout its action as possible.

The invention consists in the novel construction, combination and arrangement of 20 parts hereinafter described, pointed out in the claims, and illustrated in the accompanying drawings, and in order that the invention may be readily understood reference will now be made to said drawings, in which:—

25 Figures 1 and 2 represent a side elevation of my improved baling-press. Fig. 3 is a plan view of the press with the delivery ends of the baling-cases broken away. Fig. 4 is a side elevation of the same with the pitchers, 30 forming part of the invention, in reverse positions to that shown in Fig. 3. Fig. 5 is a vertical section taken on line V—V of Fig. 3 with the pitchers in the same position shown in Fig. 4. Fig. 6 is a vertical central section 35 taken on line VI—VI of Fig. 3. Fig. 7 is a transverse section taken on line VII—VII of Fig. 3. Fig. 8 is a broken horizontal section on line VIII—VIII of Fig. 6. Fig. 9 is a broken plan view of one of the baling-cases 40 with a tension device for regulating the discharge end thereof.

In carrying out the invention I employ a pair of baling-cases 1 2 arranged in horizontal alignment and separated by a centrally-disposed cylinder 3 secured to the adjacent ends of the baling-cases by lugs 4 5 and rods 6. The baling-cases consist of side-plates 7, bottom plates 8, top-plates 8^a and angle-irons 9.

10 and 11 designate front and rear axles, 50 respectively, upon which are mounted wheels 12 employed in transporting the press from place to place. Axle 10 is swiveled upon a king-bolt 13 so that the press may be readily turned in any direction.

55 14 designates a pair of rearwardly diverg-

ing braces which assist in securing the rear axle to baling-case 2.

15 16 designate hoppers communicating, respectively, with the upper portions of baling-cases 1 2. 60

17 designates a partition partly separating the hoppers from their respective baling-cases, and covering the top of cylinder 3.

18 designates a fender secured to one side of the feed openings in the hoppers to prevent the hay, or other material being baled, 65 from being thrown beyond said feed-openings.

19 20 designate a pair of curved aprons secured to the opposite side of the feed-openings and supported at their lower ends by braces 21 22, provided at their upper ends with stop-blocks 22^a and secured at their lower terminals to lugs 23 projecting from irregular-shaped castings 24 25, provided with 70 pockets 24^a 25^a, respectively.

Charges of material are alternately thrown upwardly into the hoppers by a pair of oscillatory pitchers 26 27, each of which comprise a sheet-metal plate 28, for the reception of 80 the material, and a U-shaped rod 29 to which said plate is secured. Rods 29 are pivotally mounted in brackets 30 31 secured to the adjacent sides of the hoppers.

32 designates bars secured to rods 29 and 85 adapted to contact with blocks 22^a and support the pitchers when the latter are in their lowermost positions.

The pitchers are alternately drawn upwardly with their charges of material by cables 33, extending over sheave-wheels 34 34^a and attached at their ends to bars 32 and the free ends of a pair of links 35, which are pivotally secured at their opposite ends to a rod 36 extending transversely through the forward ends of a pair of connecting-bars 37. 90 As it is desirable to have the pitchers remain in their lowermost positions as long as possible to give ample time to charge them with material, cables 33 are of sufficient length to 100 have a certain amount of slack when said pitchers are down, hence when the uppermost pitcher starts downwardly the lowermost pitcher will remain at rest until all of the slack in its cable is taken up. The pitchers 105 are started downwardly by springs 27^a which push against bars 32.

Connecting-bars 37 are pivotally secured at their rear terminals to a pair of oscillatory levers 38, fulcrumed upon studs 39, project- 110

ing from castings 40, secured to the sides of baling-case 2. Said levers have lower forked ends 41 loosely embracing antifriction rollers 42, mounted upon the outer terminals of a shaft 43, carrying another pair of antifriction rollers 44, arranged to travel in guides 45 projecting from the opposite sides of baling-case 2.

46 designates a shaft extending through baling-case 1 and provided at its ends with antifriction rollers 47, arranged to travel in guides 48, projecting from the opposite sides of baling-case 1 and arranged in horizontal alignment with guides 45.

15 A designates a piston comprising a rod 49 and a head 50 which latter is secured midway between the ends of the former and reciprocably arranged in the cylinder 3. The ends of the piston-rod are connected to shafts 43 20 46 by links 51 so that any vibratory motion which may be transmitted by rollers 44 47 to shafts 43 46 will not be imparted to the piston-rod and tend to cause the latter to operate in the stuffing-boxes of the cylinder with 25 undue friction.

B C designate a pair of plungers arranged to traverse baling-cases 1 and 2, respectively, and comprising head-blocks 52 53, mounted upon rollers 54, and a pair of toggles comprising links 55 56 which latter have extensions 57. Said extensions engage castings 24 25, as shown in Fig. 6, and cause the toggles to unfold while alternately making their forward strokes, and remain extended until 30 they are folded by rollers 58 59 engaging pockets 24^a 25^a, respectively, as the toggles alternately complete their backward strokes. The rollers 58 59 are mounted upon shafts 60 extending through links 56. By interposing 35 the toggles between the piston-rod and the head-blocks it is obvious that longer strokes will be imparted to the latter, and, consequently, larger feed-openings in the baling-cases will be obtained.

45 61 62 designate a pair of aprons adapted to receive the charges of material as they are alternately thrown into the hoppers by the pitchers. The rear adjacent ends of said aprons slide upon partition 17 and their forward portions are loosely secured to the respective head-blocks by segmental links 63, so their forward down-turned ends 64 65 may perform the function of tuckers and push the material forwardly beneath the top-plates of 50 the baling-cases, and thus prevent the material from binding between said plates and the tops of the head-blocks. The forward ends of the aprons are yieldingly held in a raised position by coil-springs 66 so that 55 when they move forward they will bear against the top plates and prevent portions of the material from lodging between their forward down-turned ends and the top-plates. Springs 66 embrace the lower portions of rods 67 depending from the tops of 60 65

the head-blocks and provided at their lower threaded terminals with nuts 68 whereby the tension of the springs may be regulated.

69 designates a condenser reciprocably arranged in the hoppers to initially compress the charges before they are pushed downwardly into the baling-cases. Said condenser is mounted upon rollers 70, journaled upon shafts 71, carried by brackets 31, and is prevented from tipping on said rollers when 75 at the end of a stroke by transverse rods 72 extending through the adjacent ends of the hoppers and engaging the upper surface of a pair of parallel bars 73 forming part of the condenser. As rod 36 extends through 80 the bars 73 the condenser will be moved simultaneously in reverse directions to that traveled by the plungers through the instrumentality of the connecting-bars 37 and levers 38, hence when plunger C is at the end 85 of a backward stroke the condenser will have compressed the charge in hopper 15 preparatory to its being forced downwardly in front of said plunger.

The admission of steam or other motive 90 fluid to cylinder 3 is controlled by a balanced valve, not shown, slidably arranged in a valve-case 74 fixed to the cylinder. Said valve is provided with a stem 75 extending in opposite directions and provided with collars 76 fixed thereto equal distances from the ends of the valve case.

77 designates a pair of coil springs interposed between the collars and the ends of case 74 for the purpose of holding the valve 100 in a central position so that it will normally cut off the flow of fluid to the cylinder.

78 79 designate a pair of bell-crank levers fulcrumed to baling-cases 1 and 2, respectively, and pivotally secured at their opposite ends to the terminals of stem 75 and the lower ends of push-bars 80 81, respectively, extending through eyes 82 on the baling-cases. Said push-bars are provided at their upper ends with foot-plates 83 84, respectively, so that an attendant standing on each baling-case may alternately operate the valve. The density of the bales will be regulated by tension devices on the delivery ends of the baling-cases. Each tension device 110 consists of a toggle comprising a pair of tension-bars 85, extending across the top and bottom of the case, and a member 86 pivotally secured to the adjacent ends of the bars by a rod 87. The opposite ends of bars 85 115 are pivotally secured to a rod 88 extending through brackets 89. Member 86 is provided at one side with an eye 90 and at its opposite side with a pair of arms 91 bearing in angle-plates 92 on the adjacent side of the 120 baling-case.

93 designates a hand-lever fulcrumed to a casting 94 secured to the side of the baling-case and provided with a notched sector 95 for receiving a detent 96 carried by the lever. 130

97 designates a connecting-rod pivotally secured at one end to the hand-lever and extending through eye 90 at its opposite threaded end which is provided with a tension-nut 98.

5 Arms 91 are set at an angle to tension-bars 85 so that when the connecting rod is drawn in the direction indicated by arrow *a* the delivery end of the baling-case will be contracted by forcing its opposite sides inwardly with arms 91 and the tension-bars.

10 In practice, when the parts are in the position shown in Fig. 6, the attendant standing upon baling-case 1 pushes the initially com-

15 pressed charge of material from hopper 15 down into said baling-case. He then depresses push-bar 80 and holds the same in a depressed position until head-block 52 completes a forward stroke and finally com-

20 presses the charge. As head-block 52 moves forward the condenser will move in a reverse direction and compress the charge of material previously deposited in hopper 16 by pitcher 27. As the condenser moves to the

25 left it will, through the instrumentality of the connecting parts, raise pitcher 26 so that another charge will be deposited in hopper 15. When head-block 52 reaches the end of its forward stroke the attendant on case 1 re-

30 leases the push-bar 80 so that the motor will stop. The attendant standing upon case 2 may then push the charge downwardly into said case and depress push-bar 81 so that head-block 53 will advance and compress

35 said charge. Thus it will be understood that the pitchers alternately deposit the charges in the hoppers, that the condenser alternately compresses said charges, and that they are finally compressed by the plungers in the

40 baling-cases; and as these parts are primarily operated by the motor and have positive connections either with each other or the piston-rod they will always operate in proper time, and each will perform its function with-

45 out interference with the other. And by arranging them to work alternately, as above described, a charge will be compressed at each stroke of the piston-head.

Having thus described my invention, what 50 I claim and desire to secure by Letters-Patent, is:—

1. A baling-press provided with a baling-case having a pocket, a head-block arranged to travel in said case, a toggle connected to said head-block and adapted to move therewith in an extended position a portion of its stroke, means for operating the toggle, and means carried by the toggle for engaging the pocket, whereby said toggle is folded when 55 completing a backward stroke.

2. A baling-press provided with a baling-case having a pocket, a head-block arranged to travel in said case, a toggle connected to said head-block and adapted to move therewith in an extended position a portion of its

stroke, a reciprocatory piston, links pivotally connecting said piston to the toggle, and means carried by the toggle for engaging the pocket, whereby said toggle is folded when completing a backward stroke.

70

3. In a baling-press provided with a baling-case, a plunger arranged to travel therein, an apron having a down-turned forward end, and yieldingly supported links pivotally connected to the forward end of said apron 75 and the upper portion of the plunger, so that the forward end of the apron may be depressed by and pass beneath the upper wall of the baling-case.

4. In a double-acting baling-press provided with two hoppers and two baling-cases, a partition partly dividing said hoppers from the cases, plungers arranged to travel in said cases, and aprons yieldingly connected at their forward ends to the 80 plungers so that said ends may be depressed by and pass beneath the upper walls of the cases, the rear ends of said aprons being arranged to slide upon the partition.

5. In a double-acting baling-press provided with two aligned hoppers and two baling-cases communicating with said hoppers, plungers arranged to travel in said cases and controlled therefrom, and a reciprocatory condenser in the hoppers arranged 90 to coöperate with said plungers.

6. In a double-acting baling-press provided with two aligned hoppers and two baling-cases communicating with said hoppers, plungers arranged to travel in said 100 cases and controlled therefrom, and a reciprocatory condenser in the hoppers which is actuated by said plungers.

7. In a double-acting baling-press provided with two aligned hoppers and two baling-cases communicating with said hoppers, a reciprocatory plunger in each case, means controlled from the baling cases and connecting said plungers so they will move together in the same direction, and a reciprocatory condenser in the hoppers arranged to simultaneously travel in reverse directions to 110 said plungers.

8. In a baling-press having a hopper and a baling-case communicating with each other, 115 a reciprocatory plunger in the baling-case, a reciprocatory condenser in the hopper, an oscillatory lever actuated by the plunger, and a connecting-bar secured to said lever and the condenser.

120

9. In a baling-press having a hopper and a baling-case communicating with each other, a reciprocatory plunger in the baling-case provided with antifriction rollers, oscillatory levers having forked ends engaging said rollers, connecting-bars secured to said levers, and a reciprocatory condenser in the hopper secured to the connecting-bars.

125

10. In a double-acting baling-press provided with two hoppers, oscillatory pitchers 130

for charging said hoppers with material, and a reciprocatory condenser in the hoppers for compressing said material.

11. In a double-acting baling-press provided with two hoppers, oscillatory pitchers for alternately charging said hoppers with material, and a reciprocatory condenser in the hoppers for alternately compressing said material.
12. In a double-acting baling-press provided with two hoppers, oscillatory pitchers for charging said hoppers with material, a reciprocatory condenser in the hoppers for compressing said material, and means connecting said pitchers to the condenser so the former will be operated by the latter.

13. In a double-acting baling-press provided with two hoppers, oscillatory pitchers adapted to alternately swing upwardly and charge the hoppers with material, a reciprocatory condenser in the hoppers for compressing said material, and means for starting the pitchers downwardly.

14. In a double-acting baling-press provided with two hoppers, oscillatory pitchers adapted to swing upwardly and charge the hoppers with material, a reciprocatory condenser in the hoppers for compressing the material, cables connecting the pitchers to said condenser, and resilient means for starting the pitchers downwardly.

15. In a double-acting baling-press provided with two baling-cases, the combination of a reciprocatory motor carried by the press, plungers arranged in the cases and actuated by said motor, and means carried by each case for controlling the motor.

16. In a double-acting baling-press pro-

vided with two alined baling-cases, the combination of a reciprocatory motor separating 40 said cases, reciprocatory plungers arranged in the cases and actuated by said motor, and means carried by each case for independently controlling the motor.

17. In a baling-press provided with a baling-case, a tension device for contracting the discharge end of said case, a hand-lever fulcrumed upon the case, a connecting-rod secured at its ends to said tension device and the hand-lever, a notched sector secured to 50 the case, and a detent carried by the lever and adapted to engage said sector.

18. A double-acting baling-press provided with two baling-cases, head-blocks therein, a motor for actuating said head-blocks, a valve 55 for controlling the admission of motive fluid to said motor, resilient means for normally holding the valve closed, a stem extending in opposite directions from said valve, levers fulcrumed on the baling-cases and connected 60 to the ends of said stems, and push-bars for actuating said levers.

19. A baling-press provided with a baling-case, a head-block arranged to travel in said case, a toggle for actuating said head-block, 65 provided with an extension, means in the path of said extension for unfolding the toggle, said means having a pocket, and rollers on the toggle adapted to enter said pocket and fold the toggle.

In testimony whereof I affix my signature, in the presence of two witnesses.
